CASKET PROTECTOR

Elisha H. Scott, Richmond, Ind., assignor to
W. N. Johnson Automobile Sheet Metal Works,
Richmond, Ind., a corporation of Indiana

Application November 20, 1933, Serial No. 698,744

15 Claims. (Cl. 27—35)

This invention relates to improvements in casket protectors, and has for its object to provide a casket protector that is simple in construction, easily operated, composed of few parts, and inexpensive.

It is particularly the object of this invention to provide a casket protector, the parts of which are composed of sheet metal, with means to connect the various parts at the grave or other point of use.

These and other objects will appear from the following description taken in connection with the drawings.

Referring to the drawings:

Figure 1 is a top plan view of the casket protector.

Figure 2 is a bottom plan view.

Figure 3 is a side elevation.

Figure 4 is a view showing the end member of the protector.

Figure 5 is a sectional view showing the grave with the protector located therein. In this figure the box containing the casket is shown in dotted lines.

Figure 6 is a vertical, longitudinal section through the protector.

Figure 7 is a section on the line 7—7 of Figure 6.

Figure 8 is a section on the line 8—8 of Figure 7.

The casket protector is a casing or box composed of parts made from sheet metal. There are altogether five parts of the protector, suitably connected for grave purposes. The protector has a base 1, which has downwardly extending end and lateral vertical walls 2, with outwardly extending flanges 3 thereon.

This base may be made in any suitable manner, and has across the floor part thereof struck-up ribs 4 on which the box containing the casket is supported. Supported on the lateral flanges of the base are side members, each of which is composed of a lateral wall 5, a bottom flange 6, an arcuate top 7, a vertical extension 8 on the top, and an outwardly extending projection 9 on the vertical extension. Each end of each side member has therein a bead forming a groove 10. These grooves, when the side members are assembled, receive the end members and aid in supporting the end members.

Each lateral wall has at each end a bracket 11, which has therein a hole 12. These brackets extend horizontally inwardly from the side wall and at right angles thereto. Each end is indicated by the numeral 13, and has thereon

a bottom flange 14 adapted to engage the flange 3 at the end of the base. Each end has lateral edges 15 and an arcuate top 16. These ends have adjacent each lateral edge a bracket 17 adapted to receive between it and the end, one of the brackets 11 on the side wall of the casket protector. Each bracket 17 has a projection 18 thereon extending toward the end for projecting into the hole 12 so that the end may be held assembled with relation to the side members.

The side members are assembled so that the vertical extensions 8 lie side by side. With the side members thus positioned a lock member 19 is caused to engage these vertical extensions and the outward projections 9. For engaging these parts this lock member is provided with a substantially horizontal central and upper part, and downwardly extending, converging edges 20, between which the vertical extensions and the outwardly projecting parts are received. These parts assembled are fully shown in Figure 7.

When the side members are assembled and locked in position by means of the lock member, as shown in Figure 7, the brackets 11 will project between the ends and the bracket 17 with the projections 18 extending into the holes 12. It is understood that the side members and the end members, when assembled, rest upon the flanges of the base and engage the vertical walls, as shown in Figure 7. The lock member 19 is provided at one end with a stop 21, which is a continuation of the horizontal part of the lock member bent down to inclose the space between the converging edges.

It will be observed that this protector is composed of a base forming the bottom, two side members and two end members, the side members being held together by means of the lock member 19, while the end members are held in proper position with relation to the side members by means of the brackets 11 and 17. No keys, screws, bolts or rivets are used. The parts are easily assembled, easily disassembled, and when assembled form a substantial container for a casket or a box containing a casket.

It will be understood that I desire to comprehend within this invention such modifications as come within the scope of the claims and the invention.

Having thus fully described my invention, what I claim as new and desire to secure by Letters Patent, is:

1. In a casket protector, a pair of side members, each formed to provide a lateral wall, an arcuate top and an extension on the top, and

- means to releasably engage the extensions to hold the side members together.
2. In a casket protector, a pair of side members, each formed to provide a lateral wall, an 5 arcuate top and an extension on the top, and means adapted to slide over the extensions to hold the side members together.
3. In a casket protector, a pair of side members, each having a lateral wall part, an arcuate 10 top part and an outwardly extending projection on the top part, and means inclosing the projections to hold the side members together.
4. In a casket protector, a pair of side members, each having a lateral wall part, an arcuate 15 top part and an outwardly extending projection on the top part, and means inclosing the projections to hold the side members together, said means comprising a member having downwardly converging projection-engaging parts.
5. In a casket protector, a pair of sheet metal 20 side members, each having a lateral wall part, an arcuate top part, a vertical extension, and an outwardly extending projection, and means to engage the projections to hold the side members together.
6. In a casket protector, a pair of sheet metal 25 side members, each having a lateral wall part, an arcuate top part, a vertical extension and an outwardly extending projection, and means to engage the projections to hold the side members together, said means consisting of a lock member having downwardly converging parts to engage the projections.
7. In a casket protector, a pair of sheet metal 30 side members, each having a lateral wall part, an arcuate top part, a vertical extension and an outwardly extending projection, and means to engage the projections to hold the side members together, said means consisting of a lock member having a horizontal part resting on the projections and downwardly converging parts engaging the outer surfaces of the projections.
8. In a casket protector, a pair of side members forming the side walls and the top of the 35 protector, means to releasably hold the side members together, ends, brackets on each end parallel to and slightly spaced from the end, and brackets on the side members adapted to fit between the ends and the end brackets.
9. In a casket protector, a pair of side members forming the side walls and the top of the 40 protector, means to releasably hold the side members together, ends, brackets on each end parallel to and slightly spaced from the end, and
- brackets on the side members adapted to fit between the ends and the end brackets, said end brackets having holes and the side member brackets having projections to fit in the holes of the end brackets. 80
10. In a casket protector, a pair of sheet metal side members forming the side walls and the top of the protector and having their ends formed to provide grooves, means to hold the side members together, ends adapted to fit in the grooves, brackets on each end parallel to and slightly spaced from the end, and brackets on the side members adapted to fit between the ends and the end brackets. 85
11. In a casket protector, a pair of sheet metal side members forming the side walls and the top of the protector and having their ends formed to provide grooves, means to hold the side members together, ends adapted to fit in the grooves, brackets on each end parallel to and slightly spaced from the end, brackets on the side members adapted to fit between the ends and the end brackets, and means to cause the brackets to interengage. 90
12. In combination, a base having supporting flanges, a two-part cover supported by and aligned with the base, a top lock for the cover parts, and end members supported by the base and interlocking with the cover parts. 100
13. In a casket protector, a pair of side members forming the side walls and top of the protector, means to releasably hold the side members together, ends, brackets on each end, and brackets on the side members adapted to interlock with the end brackets. 105
14. In a casket protector, a pair of sheet metal side members forming the side walls and the top of the protector and having their ends formed to provide grooves, means to hold the side members together, ends adapted to fit in the grooves, brackets on each end, and brackets on the side members adapted to interlock with the brackets on the ends. 110
15. In a casket protector, a pair of sheet metal side members forming the side walls and the top of the protector and having their ends formed to provide grooves, means to hold the side members together, ends adapted to fit in the grooves, brackets on each end, brackets on the side members adapted to interlock with the brackets on the ends, and means to hold the brackets interlocked. 115
